UNITED STATES PATENT OFFICE.

CARL EUGEN LINDGEEN, OF STOCKHOLM, AND GEORG KARL VILHELM JOHANSON, OF SKARSATRA, SWEDEN.

APPARATUS FOR DRYING SAFETY RAZORS.

Application filed December 17, 1924, Serial No. 756,401, and in Sweden August 6, 1924.

It is a well known fact that safety razors are very difficult to clean after use. When the razor has been rinsed or washed in water for removing the soap lather from the 5 same, it must be very carefully dried in order to prevent the blade and the other parts of the razor from becoming rusty. This entails the risk of cutting one's fingers, and it might also easily happen that the towel 10 or the like means of which the blade is dried, is cut by the sharp blade and is thus ruined.

The present invention relates to an apparatus for drying safety razors through the 15 use of which the said inconveniences will be avoided. The new apparatus consists principally of a device for putting the razor in rapid rotation around the axis of its shaft or handle. In this manner the water on 20 the razor will be rapidly thrown off, so that the razor will become dry in a few moments, particularly if it was previously rinsed in hot water, as is usual. In practice, the 25 said device may be constructed in different ways. For instance, a securing or gripping device for the handle of the razor may be provided in a suitable frame, casing or the like, which device is connected through a 30 gearing in the frame or the like with a crank or similar driving member in such manner that the gripping device and thus also the 35 razor secured in the same may be put in rapid rotation around the longitudinal axis of the handle. The frame or the like in which the gearing is provided, may be constructed in such manner that it forms a 40 portion of the case for the razor, so that said case may serve as a handle for holding the device during the rotation.

In the accompanying drawing two embodiments of the invention are shown by 45 way of example. Fig. 1 shows an apparatus according to the invention in side view and partly in section, and Fig. 2 shows a cross section of the apparatus. Fig. 3 shows a 50 side view of a slightly modified construction in which the apparatus is built into a case for keeping the razor, in the manner above referred to.

In the embodiment illustrated in Figs. 1 55 and 2, 1 denotes the casing in which a gearing is provided, which in the embodiment illustrated consists of a worm wheel 2 and a worm 3. To the shaft 4 of the worm wheel 2, which shaft is journaled in the two

opposite walls of the casing 1, a crank 5 is secured by means of which said worm wheel may be rotated. The crank 5 proper has a forked end which is pivoted by means of a pin 6 to a member 7 secured to the shaft 60 4 in such manner that the crank may be turned over from the position shown in Fig. 2 with dotted and dashed lines and which the crank is to occupy when the device is operated, into the position shown in Fig. 65 2 with full-drawn lines in which the knob on the crank enters an aperture in the casing 1. In this manner the advantage is attained that when not in use the device 70 requires little space.

The worm 3 is journaled in a sleeve 8 in which a ball 8^a is provided against which one end of the worm spindle bears, and in a bearing 9, and it supports at its other end which projects outside the casing 1, a gripping device in which the shaft 10 of the 75 razor to be dried may be secured. In the embodiment illustrated in Fig. 1, said gripping device consists of a round cup or sleeve 11 secured to the worm spindle, and in 80 which two disks 12 of rubber or similar elastic material are secured. The disks are provided with holes at their centers, in which the handle 10 of the razor may be inserted, so that the razor will be held by the elastic 85 disks. The use of such elastic disks entails the advantage that the gripping device may serve for holding razor shafts of various diameters, so that the device may be used for practically all existing constructions of 90 razors. The worm 3 is retained in the casing by a thin spring 13 which passes through a slot 14 in the bearing 9 and engages a peripheral groove in the worm spindle, and thus prevents the worm 3 from movement in an axial direction. When it is desired to take out the worm from the casing 95 1, the spring 13 may be moved out of engagement with the groove in the worm spindle by exerting pressure on a knob 15 which projects outside the casing 1 and which engages the spring 13, after which the worm 100 may be pulled out of the casing in the direction upwards in Fig. 1.

When the razor has been rinsed, preferably in hot water, the shaft 10 of the razor is inserted in the gripping device 11, 12 in the manner illustrated in Fig. 1. While the casing 1 is held with one hand the crank 5 is rotated with the other hand in the di- 105 110

rection indicated by the arrow in Fig. 1. Through the gearing 2, 3 the gripping device 11, 12 and thus also the razor held in the same are in this manner put in a very rapid rotation around the axis of the shaft 10, and the water on the razor is rapidly thrown off owing to the centrifugal force. It is therefore possible, as a rule, by turning the crank 5 through a few revolutions 10 to dry the razor completely.

According to Fig. 3 the casing 1 in which the gearing is located is built into a case 16 which serves for keeping the razor 17 and a strop 18, and so forth. The apparatus 15 is thus in this case intended to be sold together with the razor for which it is to be used, and the securing device needs thus only be constructed in such manner that it fits this particular razor. The razor is in 20 the instance illustrated supposed to be provided with a hollow shaft or handle, and in accordance herewith the securing device consists of a slotted resilient pin 19 secured to the worm of the gearing, and which is 25 so dimensioned that it fits into the hollow shaft. It is thus only necessary to push the shaft onto the pin. The case 16 may suitably serve as a handle for holding the device while the crank 5 is turned. The crank 30 may advantageously be removable, so that the crank may be placed in the case 16, when the device is not used, together with the worm which may be adapted to be withdrawn from the casing 1, in the manner 35 above described.

The worm gearing above described may of course be replaced by any other suitable gearing, by means of which the gripping or securing device for the shaft or handle 40 of the razor may be rapidly rotated.

The embodiments of the invention above described and illustrated in the drawings are only to be regarded as examples, and it will be evident that the same may be modified in several ways in regard to their 45 details without departing from the principle and scope of the invention.

We claim:

1. An apparatus for drying safety razors, 50 comprising in combination a frame, a securing device rotatably journalled in said frame and adapted to receive and hold the

shaft of a safety razor with its axis substantially in alignment with the axis of rotation of said securing device, driving means 55 in said frame, and a gearing between said driving means and said securing device whereby the latter may be rapidly rotated from said driving means.

2. An apparatus for drying safety razors, 60 comprising in combination a frame, a spindle rotatably journalled in said frame, resilient means carried by said spindle and adapted to receive and hold the shaft of a safety razor with its axis substantially in 65 alignment with the axis of said spindle, driving means in said frame, and a gearing between said driving means and said spindle whereby the latter may be rapidly rotated from said driving means. 70

3. An apparatus for drying safety razors, comprising in combination a frame, a spindle rotatably journalled in said frame, resilient means carried by said spindle and adapted to receive and hold the shaft of a safety razor with its axis substantially in 75 alignment with the axis of said spindle, a shaft rotatable in said frame, means for rotating said shaft, and a gearing between 80 said shaft and said spindle whereby the latter may be rapidly rotated.

4. An apparatus for drying safety razors, comprising in combination a frame, a spindle rotatably journalled in said frame, resilient means carried by said spindle and 85 adapted to receive and hold the shaft of a safety razor with its axis substantially in alignment with the axis of said spindle, a shaft rotatable in said frame, a crank on 90 said shaft, and a gearing between said shaft and said spindle whereby the latter may be rapidly rotated.

5. An apparatus for drying safety razors, comprising in combination a frame, a spindle rotatably journalled in said frame, a 95 slotted resilient pin adapted to fit into a hollow razor shaft and mounted on said spindle in substantial alignment with the same, a shaft rotatable in said frame, a crank on said shaft, and a gearing between 100 said shaft and said spindle whereby the latter may be rapidly rotated.

CÄRL EUGEN LINDGREN.
